Patented June 27, 1922.

UNITED STATES PATENT OFFICE.

DANIEL D. DEWEY AND LEO G. SAWDY, OF ESCANABA, MICHIGAN.

TROUSERS PRESSER.

1,420,822.

Specification of Letters Patent. Patented June 27, 1922.

Application filed October 28, 1921. Serial No. 511,077.

To all whom it may concern:

Be it known that we, DANIEL D. DEWEY and LEO G. SAWDY, both citizens of the United States, and residents of Escanaba, 5 in the county of Delta and State of Michigan, have invented a certain new and useful Improvement in a Trouser Presser, of which the following is a specification.

Our invention relates to pressing devices 10 for trousers and particularly to a novel board composed of hinged sections adapted to be separated and folded into a small compass.

The presser of our invention is designed 15 primarily to provide a device of simple construction that may be collapsed and readily assembled and which will operate efficiently for the described purpose. It consists essentially of two boards each of which is 20 transversely divided thereby forming sections, and each section being provided with a hinged joint, the joints of two of the sections extending transversely of the board while the joints of the two opposing sections 25 extend longitudinally thereof. Thus the joints in the sections extend at an angle to each other and a rigid structure is assured.

The invention will be more readily understood by reference to the accompanying 30 drawings, wherein,

Fig. 1 is a view of one side of an assembled pressing device constructed in accordance with our invention;

Fig. 2 is a view of the opposite side 35 thereof;

Fig. 3 is an edge view;

Fig. 4 is a perspective view of the dismantled board, and,

Fig. 5 is a perspective view of one of the 40 spring clamps.

The device consists essentially of two boards adapted to resiliently clamp the two legs of a pair of trousers therebetween. The boards are generally designated A and B. 45 Each of these boards is transversely divided and provided with hinges 10, 11, respectively, the pivots of the hinges being readily removable and preferably consisting of stiff wires 12, 13, adapted to be inserted from 50 the side through the eyes of the hinges. The sections of the board A are likewise transversely divided thereby forming portions 14, 15, 16, 17. The parts of the hinges 18 are not separable as in the case of the hinges 55 10, 11, there being no occasion for this as

the pieces of the sections may be folded back to back and occupy the minimum of space.

The sections of the board B are longitudinally divided forming pieces 19, 20, 21, 22, these pieces being united by hinges 23, the 60 parts of which are likewise inseparable, the pieces of the two sections being folded back to back and substantially conforming in size to the folded sections of the board A.

Spring clips or fasteners 24, as best shown 65 in Fig. 5, are employed for clamping the boards A, B, over the trouser legs. A hook 25, having sliding engagement with a keeper 26, provides means for hanging the trousers as desired. When not in use the hook may 70 be slid longitudinally into the plane of the board. The view in Fig. 4 is that of the dismantled boards showing the small space occupied by the parts when in that condition.

In operation and with the device assembled as shown, the two legs of a pair of trousers are carefully placed on one board and the other board located in proper position. The spring clamps are then suitably 80 positioned in order to equalize the pressure at various points around the board and the parts allowed to remain in the described position for a suitable length of time, usually over night. The clamping action of the 85 spring clips is uniform and the pressing action will be found to be thorough. When the device is not in use or in case it is employed by men who travel, it may be quickly dismantled and folded into the compass indicated in Fig. 4. A fabric container may be provided and the presser carried either in that manner or in a suitcase or bag. It will be constructed of light weight material, preferably laminated sections of board, 95 so disposed that the grain of adjacent sections extend at right angles.

Obviously the construction is capable of much modification and we do not wish to be limited except as indicated in the appended 110 claims.

We claim:

1. In a pressing device, the combination of a pair of pressing boards, means for clamping the same together, each of said 105 boards being transversely divided at a point substantially midway between its ends, hinges joining the divided sections of each board, the sections of one board being additionally transversely divided and hinged, 110

and the sections of the other board being longitudinally divided and hinged.

2. In a device of the class described, the combination of a pair of boards, means for 5 clamping trouser legs therebetween, each of the boards being transversely divided and hinged at a point between its ends, means permitting ready separation of the hinged sections, each of the hinged sections of each 10 board being subdivided and hinged, the division lines of two of the sections being transverse and the division line of the other two sections being longitudinal of the boards, the sections being so disposed that 15 the transverse and longitudinal division lines are in opposed sections.

3. In a device of the class described, the combination of a pair of boards, spring clips for clamping trouser legs therebetween, each of the boards being transversely 20 divided and hinged at a point between its ends, means permitting ready separation of the hinged sections, each of the hinged sections of each board being additionally divided and hinged, whereby each board may 25 be separated into two sections and the parts of each section be folded back to back.

Signed at Escanaba, Mich., this 20th October, 1921.

DANIEL D. DEWEY.
LEO G. SAWDY.
